UNITED STATES PATENT OFFICE

163,652

LENS RIM MATERIAL FOR SPECTACLE
FRAMES

Raymond F. E. Stegeman, Greece, N. Y., assignor
to Bausch & Lomb Optical Company, Rochester, N. Y., a corporation of New York

Application April 9, 1949, Serial No. 1,882

Term of patent 14 years

(Cl. D57—1)

To all whom it may concern:

Be it known that I, Raymond F. E. Stegeman, a citizen of the United States and a resident of the town of Greece, county of Monroe, and State of New York, have invented a new, original, and ornamental Design for Lens Rim Material for Spectacle Frames, of which the following is a specification, reference being had to the accompanying drawing, forming a part hereof.

Fig. 1 is a side view of a portion of lens rim material for spectacle frames, showing my new design.

Fig. 2 is a top plan view thereof.

Fig. 3 is a sectional view taken on line 3—3 of Fig. 2.

My design for lens rim material for spectacle frames is characterized by the spiraled lines crossing the top and extending partially down on the sides and with the sides of the lens rim material straight and substantially parallel to each other, all as illustrated.

I claim:

The ornamental design for lens rim material for spectacle frames, substantially as shown and described.

RAYMOND F. E. STEGEMAN.
